KNITTED ARTICLE AND METHOD OF
MAKING SAMEGustav Gastrich, Wyomissing, Pa., assignor to
Textile Machine Works, Wyomissing, Pa., a
corporation of Pennsylvania

Application March 10, 1934, Serial No. 714,911

10 Claims.

(Cl. 66—178)

My invention relates to knitted fabrics, particularly stockings, whereon markings, information tags or like elements are provided.

It has been a practice of certain unscrupulous dealers, especially in the field of full fashioned stockings wherein the market is extensive and the competition keen, to dispose of "seconds", which have imperfections therein, as perfect stockings or "firsts", by altering, removing, destroying or substituting markings or tags usually applied to seconds to indicate that such stockings are imperfect.

It is, therefore, an object of the invention to subvert such practice by providing an information tag of such character, position and installation by a knitting operation incident to the manufacture of a stocking, that the tag cannot thereafter be either partially or entirely removed, or altered, without leaving a clear indication of such attempt, and a like tag may not be substituted or similarly installed in any finished stocking.

Thus, a manufacturer, by appropriately marking the tags, is protected against unfair competition, against the return of seconds or lower grades for superior grades of the same stock, the return of old for new stock, and like practices; the jobbers and retailers are protected as to each other and also, in certain respects, as to retail customers; discriminating purchasers are protected as are the manufacturers and dealers, and the general purchasing public is protected to a substantial extent so far as affected by this particular feature of unfair trade practices.

Tags have, in general, been heretofore employed on stockings, but none of them, so far as I am aware, have conduced to the kind or degree of protection herein contemplated, or have taken into consideration, as well, other features such as comfort to the wearer, attractiveness of design, lack of objection to their presence, facility of installation and inspection, and permanency of character, irrespective of certain manufacturing and service effects occurring subsequent to the installation thereof; it being among the objects of the invention to overcome the objections of prior similar attempts, to provide the advantages above indicated, and to provide a combined stocking and marker structure that shall be simple and durable in construction, economical to manufacture, and effective in its operation.

A further object of the invention is to provide a method of and a means for, marking and rendering permanent the identification of, speci-

mens produced in experimental or research work wherein such marking and identification has heretofore particularly been of more or less nondescript and temporary character.

With these and other objects in view, which will become apparent from the following detailed description of the illustrative embodiments of the invention shown in the accompanying drawings, my invention resides in the novel fabrics and articles, and method of producing the same, as hereinafter more particularly pointed out in the claims.

In the drawings:

Figure 1, of the accompanying drawings, is a perspective view of a combined stocking and tag structure of the invention, as viewed from the rear and with the stocking extended, as in actual service form;

Fig. 2 is a detail view, on an enlarged scale, and taken substantially along the line 2—2 of Fig. 1, of a top portion of the structure thereof, part being broken away for purposes of illustration;

Fig. 3 is a face view of a tag or marker of one form suitable to the invention;

Fig. 4 is a view, similar to Fig. 3, of a tag of another form adapted to the invention;

Fig. 5 is a fragmentary detail view, on a greatly magnified scale, of a portion "A" of the structure, as viewed in Fig. 2;

Fig. 6 is a view taken substantially along the line 6—6 of Fig. 5; and

Figs. 7, 8, 9 and 10 are diagrammatic views of portions of a knitting machine, a stocking and a tag, in successive stages of the manufacture of the stocking and the installation of the tag in accordance with the invention.

The information tag may be applied to any part of the stocking or other knitted article, for any purpose, during the fabrication of the article, altho in the specific embodiment illustrated herein is shown as applied to the welt.

Referring particularly to Figs. 1 and 2, a tag 12 is mounted between inner and outer layers 14 and 15, respectively, of the welt of a stocking 16, being knitted in place at the welt line 17 adjacent to the rear seam 18 and to the opening 19, left by the seaming machine, in the inner welt layer 14, in a manner and for a purpose, which will hereinafter more fully appear.

The tag 12, preferably composed of limp or soft, washable, substantially solid material, may be of any of various forms, and may have designs or characters on one or both sides. Where the welt fabric is sufficiently sheer, the tag may be

viewed directly through it, and the characters designed accordingly, as to color, density and the like, both as to facility of reading the tag and as to any esthetic relation which it is desired to have between the stocking and the tag. The tag, or a portion thereof, may be of a nature such that certain marks, as of pencil or ink, of a temporary and removable character may be employed, such feature facilitating the placing and removal of temporary checking data or other information desired to be placed on the stocking without injury thereto. The tag may further be provided with an area or areas such as an area 20, upon which a grade mark may be placed after completion of the stocking, as by reaching through the opening 19; such grade mark indicating whether the stocking is a "first", "second" or "third", which grade it may not be certain the stocking will have until completed, with the tag in place. A similar area for a date may, however, be provided on which the date is indicated by characters applied after completion of the stocking, or by characters placed on the tag before mounting it in place.

It is contemplated that the fabric or texture of the tag may assume various forms and combinations of material or materials, such as being constructed of ordinary silk, or dye-resist silk, or a combination of these and other materials, and be provided in permanent color before dyeing the stocking, or of such color as to combine with the dye of the stocking to give a desired effect.

As indicated in Fig. 3, the tag 12a may be of ordinary fine knit soft fabric, such as silk, which lends itself to ready mounting on the needles of a knitting machine for installation during the construction of the stocking, in accordance with a major feature of the invention, as will appear.

In Fig. 4, a tag 12b of the same material as tag 12, or of other substantially solid material, such as tracing cloth, is provided with an edge 22 having preformed apertures 21 spaced therealong according to the gauge of the needles, whereby the tag may be thrust over the beards of the needles, without injury to the tag or to the needles; this structure also ensuring that the tag will be inserted in correct position, especially where the tag is provided with like designs or inscriptions on opposite sides.

Referring to Figs. 7 to 10, inclusive, in knitting a full fashioned stocking, the welt is first knitted flat, that is, with the inner and outer walls 14 and 15, respectively of Figs. 1 and 2, disposed as one piece in the same plane, as indicated in Fig. 7, in which it is drawn away from the needles 24 by a welt bar 25 carrying hooks 26. As indicated in Fig. 8, upon the completion of the welt, the tag 12 is topped or positioned on the needles at the welt line 17, or last course of welt thread, and the inner welt layer 14 is topped back over the outer layer 15 and over the tag 12, to top the last course of welt loops 27 over the needles; a usual welt rod 28 being employed in this operation, and to draw off the fabric during the knitting of the remainder of the leg, a portion 38 of which is indicated in Fig. 10. The tag may similarly be placed outside the welt, or a combination of tags of like or different character be placed inside and outside the welt as indicia or structural elements so far as the broad invention is concerned.

Altho the tag or tags of any suitable size or shape may extend along or around, or at any local position or positions along or about, the

stocking, in accordance with such features, a tag between the welt layers 14 and 15 may preferably be placed near the opening 19 left by the seaming machine, as indicated in Figs. 1 and 2, whereby direct access to the tag may be had for viewing it, especially where the tag can not readily be seen or read thru the wall of the welt, or for other purposes, such as marking it, as by a grade mark on the area 20 that may preferably be placed next to the opening 19. This arrangement also permits removal of the tag, if desired, by the wearer, but since it is directly and completely interlooped with yarns of the stocking body proper, such removal may only be effected, as by cutting close to the welt line, in a manner which, altho effecting substantially entire removal of the tag, leaves at least a portion which cannot be removed. The remaining portion of the tag, even if very small, clearly indicates that the tag body was present, and may itself be so marked or constituted, as by a secret inscription or thread arrangement, as to still indicate the manufacturer. In another form, the tag may be placed at a position, as at the front of the welt, in which it is substantially inaccessible through the opening 19 for removal as above indicated, in which case, altho certain of the advantages of having it adjacent to the opening are not present, the additional protection of the more certain preservation of the tag is provided.

The tag is attached during the usual knitting operation, by a simple movement and without delaying or affecting the knitting operation, or the structure of the stocking as otherwise constituted without the tag, and a subsequent tagging operation, with its attendant labor and expense, and danger of injury to the fabric, is rendered unnecessary; also, the use of paste and stickers, with the accompanying stiffness and undesirable characteristics thereof, is avoided. Being, in a preferred form, disposed flat between the welt layers, and of a suitable degree of inherent resistance to curling, the tag naturally conforms to, and is held by such layers; against curling or injury in dyeing, washing and ironing, avoids becoming uncomfortable and unsightly to the wearer, and has other advantages, which render the invention a distinct improvement in the art to which it relates.

Of course, the improvements specifically shown and described, by which I obtain the above results, can be changed and modified in various ways without departing from the scope of the invention herein disclosed and hereinafter claimed.

I claim:

1. The method of permanently attaching an information tag of a solid material to a knitted article of wearing apparel, which comprises knitting a portion of the article, pressing the tag upon the shanks of the needles adjacent to the last course knitted thereby perforating the same, placing a previously knitted course of loops of the article on the shanks of the needles over the tag, and in interlooping the tag with said courses by continuing knitting.

2. The method of permanently securing an information tag to a full fashioned stocking, which comprises knitting the welt of said stocking, perforating said tag with a single line of holes spaced in accordance with the gauge of the needles, applying the tag to the shank of the needles above the last course of the welt, topping a previously knitted course back upon the last course above

the tag, and interlooping the loops and the tag together by continuing knitting.

3. In the production of a full fashioned stocking, the method of permanently securing an information tag of solid hard faced material to the stocking, which comprises knitting the welt of the stocking, applying adjacent to an edge thereof a perforated tag to the shanks of the needles above the last course of the welt, topping a previously formed course of loops of the welt back upon the shanks of the needles above the tag, and interlooping the adjacent loops of the turned welt and the tag together by continuing knitting.
15. 4. In the production of a full fashioned stocking, the method of securing to the stocking an information tag of substantially solid material, which comprises knitting the welt of the stocking, perforating said tag by pressing the same on the shanks of the knitting needles adjacent to the last course of the welt, topping the first course back upon the shanks of the needles to form a turned welt, and in interknitting the tag to the turned welt by continued knitting.
25. 5. A knitted article of wearing apparel including an information tag secured thereto, said tag provided with a row of aligned apertures along one edge thereof, said tag having a course of the body yarn of the knitted article interlooped with the row of aligned apertures and said tag being arranged between portions of the knitted structure of the article adjoining said row of apertures in position to obstruct the complete removal of the tag without rupture of the yarn.
35. 6. A knitted article composed of yarn having a turned welt or hem portion, and a preperforated information tag composed of non-ravelable material interlooped with the joining edges of said portion, said tag being arranged within said

turned welt in position to obstruct the complete removal of the tag without rupture of some of said yarn.

7. The combination of a knitted article composed of interengaging courses of loops of yarn and an apertured information tag secured thereto by a course of said loops interlockingly engaged in apertures of said tag.

8. The combination of a knitted article composed of interengaging courses of loops of yarn and an apertured information tag secured thereto by a course of said loops interlockingly engaged in apertures of said tag, the material of said tag adapted to damage said yarn upon the tag being pulled loose from the article.

9. An article of wearing apparel formed from a knitted web composed of yarn and provided with a tag bearing information suitable to the article, said tag being composed of non-ravelable material and having a row of apertures along one edge, a loop of said yarn passing through each aperture at a position to obstruct the removal of the tag from the article or to cause rupture of the yarn or the tag if the tag is pulled loose.

10: The method of securing an information tag to a knitted stocking which comprises knitting courses of loops of yarn for the stocking, perforating a tag bearing information suitable to a knitted article and of non-ravelable material with a row of apertures along one edge spaced the same as the needles on which said courses were knitted, passing needles through the apertures of said tag to place the tag over the last of said courses, and continuing the knitting to secure the tag interlockingly with the yarn of the stocking.

GUSTAV GASTRICH.
